BOILER INSTALLATION

William L. De Baufre, Orange, N. J., assignor to
 International Combustion Engineering Corporation,
 New York, N. Y., a corporation of
 Delaware

Application June 29, 1929, Serial No. 374,716

10 Claims. (Cl. 122—235)

This invention relates to improvements in boiler installations having steam evaporating elements in their combustion chambers and employing boilers of the bent tube type having upper steam and water drums, lower mud drums and banks of tubes connecting the drums.

One of the primary objects of the invention is the provision of a boiler installation of the above character having improved natural circulation.

Another object resides in improvements in the arrangement of the connecting tubes of the boiler.

A further object resides in improvements in the manner of connecting the combustion chamber steam evaporating elements to the boiler of the installation.

How the foregoing, together with such other objects and advantages as may hereinafter appear, or are incident to my invention, are realized is illustrated in preferred form in the accompanying drawings, wherein—

Fig. 1 is a vertical section through a boiler installation embodying my improvements.

Fig. 2 is a fragmentary view of a modification of the invention, and

Fig. 3 is a fragmentary view of still another modification.

The installation comprises in general a boiler A of the bent tube type, a combustion chamber B located in front of and beneath the boiler A, burner means C, in this instance located in the front wall of the installation for introducing fuel, preferably pulverized coal, into the combustion chamber to be burned in space therein, and an eftake D for exit of the burnt products of combustion and a lower ash pit E.

The boiler A comprises a lower mud drum 4 and a plurality of upper steam and water drums, i. e., a front upper drum 5, a middle upper drum 6, and a rear upper drum 7, and front, middle and rear banks of tubes 8, 9 and 10 for connecting the lower drum to the upper drums. The front bank of boiler tubes 8 is divided into two groups, the front group 11 comprising a plurality of rows of tubes connected at their lower ends into the lower drum 4 and at their upper ends into the upper drum 5, and a rear group 12 comprising a plurality of rows of tubes connected at their lower ends into the drum 4 and at their upper ends into the middle upper drum 6. The middle bank of tubes 9 also comprises two groups of tubes, the front group 13 of which consists of a plurality of rows of tubes connected at their lower ends into the lower drum 4 and at their upper ends into the upper drum 5, and a rear

group of tubes 14 comprising a plurality of rows of tubes connected at their lower ends into the lower drum 4 and at their upper ends into the upper drum 6. The rear bank of tubes 10 comprises a plurality of rows of tubes connected at their lower ends into the lower drum 4 and at their upper ends into the rear upper drum 7.

The tubes of the various banks just described are arranged in parallel spacing, that is to say, they are aligned in rows crosswise of the boiler and also in planes perpendicular to the axes of the drums. The tubes of the rear group 12 of the front bank 8 and the tubes of the front group 13 of the middle bank 9 are bent at their upper portions so that they cross each other in the upper portion of the boiler as indicated at 15.

The upper drums 5 and 6, and 6 and 7, are connected together by means of a plurality of water circulators 16 and by a plurality of steam circulators 17, and a steam outlet 18 is provided for the rear upper drum 7.

The boiler A is provided with suitable baffling indicated at a, b, which is arranged to cause the gases of combustion to pass upwardly of the front bank 8, then downwardly of the middle bank 9, then upwardly of the rear bank 10, and finally discharge through the offtake D.

The combustion space of the combustion chamber B is largely defined by steam evaporating surfaces, and, in this instance, I have shown the side walls, only one of which appears in the drawings, lined by two sets of upright boiler tubes 19 and 20, the lower ends of the tubes of both sets being connected into a lower header 21 and the upper ends of the tubes of the set 19 being connected into an upper header 22, and the upper ends of the tubes of the set 20 being connected into an upper header 23. The rear wall of the combustion chamber is largely defined by a row of upright tubes 24 which are bent at their upper portions so as to extend in front of and in parallelism to the tubes of the front bank 8 as indicated at 25. These tubes are connected at their upper ends into the front upper drum 5. The bottom of the combustion space is defined by a row of tubes 26 extending across the bottom of the combustion chamber and inclined somewhat from front to rear. The tubes 26 are spaced sufficiently widely apart to permit of gravitating particles to pass freely through the space therebetween to the ash pit E therebelow. The lower end portions of these tubes are connected into and outside header 27 and the upper end portions thereof connect into headers or junction boxes 28 which serve to connect them to the upright tubes 24 of the rear wall, it being noted

that the lower end portions of the tubes 24 are bent outwardly and downwardly for connection into the junction boxes 28.

Water is led to the side wall tubes of the sets 5 19 and 20 from the lower drum 4 of the boiler by means of downcomers 29 leading from the drum to the lower headers 21 and water is led to the bottom and rear screens 26 and 24 from the mud drum 4 by means of downcomers 30 leading from the mud drum to the outside header 27. The upper headers 22 of the sets of side wall tubes 19 are connected to the upper front steam and water drum 5 by means of a plurality of upcomer tubes 31 and the upper headers 23 of the sets of side wall tubes 20 are connected to the upper middle steam and water drum 6 by means of a plurality of upcomers 32. From the foregoing it will be seen that the circulation is from the mud drum 4 to the header 27, then upwardly through the tubes 26, then upwardly through the tubes 24 and the inclined portions 25 thereof, and finally into the upper drum 5. The circulation in the side wall screens is upward and the delivery thereof is divided between the front and middle drums 5 and 6, the sets 19 delivering into the front upper drum 5 and the sets 20 delivering into the middle upper drum 6.

The circulation of the boiler unit A is upward in the tubes of the front group 11 of the front bank 8 from the drum 4 to the drum 5, upward in the tubes of the rear group 12 of the front bank 8 from the drum 4 to the middle upper drum 6 downward in the front group of the middle bank 9 from the upper drum 5 to the mud drum 4, downward in the rear group of the middle bank 9 from the middle drum 6 to the mud drum 4, and downward in the tubes of the rear bank 10 from the rear upper drum 7 to the mud drum 4.

From the foregoing, it will be seen that tubes 40 from the mud drum to the front steam drum form part of the middle tube bank, and that cross tubes from the mud drum 4 to the middle upper drum, 6 form part of the front tube bank, and that the water walls of the combustion chamber discharge steam into both the front and middle steam drums 5 and 6 while circulating water for these walls is drawn from the mud drum 4. The arrangement is very advantageous in that better natural circulation is afforded by providing a direct connection 45 from the front steam drum to the mud drum through tubes in the middle tube bank where generation of steam is not as active as in the front tube bank. Without these cross tubes the water separated from the steam liberated in the front 50 steam drum must return, either through short curved tubes to the middle steam drum and thence through the middle tube bank back to the mud drum, or must pass directly down through the tubes in the front bank where steam generation is 55 very rapid. In either case the circulation is restricted, the water level in the front drum being too high and the steam water ratio in the radiant heating surfaces reaching values which might be dangerous. The cross-over tubes provide useful 60 heating surface for the return circuit to the water walls and front tube bank which are connected to the mud drum.

The distribution of the delivery from the radiant heat tubes between the two front drums is 70 also advantageous in securing proper water levels in both drums and preventing the overloading of the front drum. In this connection, by virtue of the provision of the tubes 13 connecting the front steam and water drum to the mud drum, it is 75 possible to have more of the radiant heat tubes de-

liver to the front steam and water drum, than to the middle steam and water drum, without danger of overloading.

Referring to the modification illustrated in Fig. 2, it will be noted that the tube intersections of 5 the crossing tubes of the front and middle banks 8 and 9 are arranged well up in the boiler so that the products of combustion may pass mainly below the tube intersections in passing from the front bank over the baffle *a* to the second bank. 10

In the modification illustrated in Fig. 3, all of the tubes of the front bank 8a connect into the upper front drum 5a, while the middle bank 9a is divided into two groups as before, the front group of tubes connecting at their upper ends into the 15 drum 5a and the rear group of tubes connecting at their upper ends into the middle drum 6a. Water circulators 16a are connected between the upper drums 5a and 6a and between the upper drums 6a and 1a. The steam space of the upper 20 front drum 5a is connected to the steam space of the upper rear drum 7a by means of a plurality of steam circulators 11a, and the steam space of the middle upper drum 6a is connected to the steam space of the rear upper drum 7a by 25 means of a plurality of steam circulators 17b. In this modification I have shown all of the side wall tubes of the combustion chamber connected for delivery into the middle upper drum 6a by means of a plurality of upcomers 31a and 32a. 30 Otherwise the arrangement is the same as that shown in Fig. 1.

I claim:—

1. In combination, a bent tube boiler including a lower mud drum, front, middle, and rear upper 35 steam and water drums, front, middle, and rear banks of connecting tubes, the tubes of the front and middle bank being arranged so that both the front and middle upper drums are connected to the mud drum by tubes in both the front and 40 middle banks; a combustion chamber located in front of and beneath said boiler; boiler tubes defining combustion space of said combustion chamber; upcomer means from said boiler tubes to both the front and middle upper drums; and 45 downcomer means from the mud drum to said boiler tubes.

2. In combination, a bent tube boiler including a lower mud drum, a first and second upper 50 steam and water drum, and boiler tubes connecting the mud drum to the upper steam and water drums, certain tubes connecting the mud drum to the second upper drum being grouped with tubes connecting the mud drum to the first upper drum and constituting therewith a first 55 tube bank and certain tubes connecting the mud drum to the first upper drum being grouped with tubes connecting the mud drum to the second upper drum and constituting therewith a second tube bank; a combustion chamber located in front 60 and beneath said boiler; boiler tubes marginal of combustion space of said combustion chamber and subject to high heat; downcomer means leading from the lower mud drum to said boiler tubes; upcomer means leading from said boiler tubes to both the first and second upper drums; and means for introducing fuel into the combustion chamber to be burned in space therein.

3. In combination, a water tube boiler including a pair of upper steam and water drums, a lower 70 mud drum, and banks of boiler tubes connecting the mud drum to said upper drums, each bank comprising a plurality of tubes connecting the mud drum to one of the upper drums and a plurality of tubes connecting the mud drum to 75

- the other upper drum; a combustion chamber associated with said boiler; radiant heat tubes in said combustion chamber marginal of combustion space thereof; downcomer means leading 5 from the lower mud drum to said radiant heat tubes; upcomer means leading from said radiant heat tubes to both of the upper steam and water drums; and means for introducing fuel into the combustion chamber to be burned in space 10 therein.
4. In combination, a water tube boiler including a pair of upper steam and water drums, a lower mud drum, and banks of boiler tubes connecting the mud drum to said upper drums, each bank 15 comprising a plurality of tubes connecting the mud drum to one of the upper drums and a plurality of tubes connecting the mud drum to the other upper drum; a combustion chamber associated with said boiler; radiant heat tubes defining 20 the side walls of said combustion chamber; radiant heat tubes extending across the bottom of said combustion chamber; radiant heat tubes defining the rear wall of the combustion chamber and connected to deliver in the first upper drum; 25 means connecting the bottom radiant heat tubes to said rear wall tubes; downcomer means for supplying water to the bottom tubes from the mud drum; downcomer means for supplying water to the side wall tubes from the mud drum; 30 upcomer means connecting certain side wall tubes for delivery into the first upper drum; upcomer means connecting the remaining side wall tubes for delivery into the second upper drum; and means for introducing fuel into the combustion 35 chamber to be burned in space therein.
5. In combination, a bent tube boiler including a lower mud drum, front, middle, and rear upper steam and water drums, front, middle, and rear banks of connecting tubes, the tubes of the front 40 and middle bank being arranged so that both the front and middle upper drums are connected to the mud drum by tubes in both the front and middle banks, the tubes of the rear bank connecting the mud drum and rear upper drum, water circulators connecting the front and 45 middle drums and the middle and rear drums, steam circulators connecting the front and rear upper drums, and steam circulators connecting the middle and rear upper drums; a combustion 50 chamber associated with the boiler; boiler tubes defining combustion space of said combustion chamber; downcomer means from the mud drum to said boiler tubes; upcomer means from said boiler tubes to both the front and middle upper drums; and means for introducing fuel into the combustion 55 chamber to be burned in space therein.
6. In combination, a bent tube boiler including a lower mud drum, front, middle and rear upper steam and water drums, front, middle and rear banks of connecting tubes, the tubes of the middle bank being arranged so that both the front and middle upper drums are connected to the mud drum by tubes in said bank, a combustion 60 chamber associated with the boiler, boiler tubes defining combustion space of said combustion chamber, upcomer means from said boiler

tubes to the second upper drum, downcomer means from the mud drum to said boiler tubes, and steam and water circulators connecting the upper steam and water drums.

7. In combination, a bent tube boiler includ- 5 ing a lower mud drum, a first and second upper steam and water drum, and boiler tubes connecting the mud drum to the upper steam and water drums, certain tubes connecting the mud drum to the second upper drum being grouped with tubes 10 connecting the mud drum to the first upper drum and constituting therewith a first tube bank and certain tubes connecting the mud drum to the first upper drum being grouped with tubes connecting the mud drum to the second upper drum 15 and constituting therewith a second tube bank; a combustion chamber located in front of and beneath said boiler; boiler tubes marginal of combustion space of said combustion chamber and subject to high heat; downcomer means 20 leading from the lower mud drum to said boiler tubes; and upcomer means leading from said boiler tubes to both the first and second upper drums.

8. In combination, a water tube boiler includ- 25 ing a pair of upper steam and water drums, a lower mud drum, and banks of boiler tubes connecting the mud drum to said upper drums, each bank comprising a plurality of tubes connecting the mud drum to one of the upper drums and a 30 plurality of tubes connecting the mud drum to the other upper drum; a combustion chamber associated with said boiler; radiant heat tubes in said combustion chamber marginal of combustion space thereof; downcomer means leading 35 from the boiler to said radiant heat tubes; and upcomer means leading from said radiant heat tubes to the boiler.

9. In combination, a bent tube boiler includ- 40 ing a lower mud drum, front, middle, and rear upper steam and water drums, front, middle, and rear banks of connecting tubes, the tubes of the front and middle bank being arranged so that both the front and middle upper drums are connected to the mud drum by tubes in both the 45 front and middle banks, the tubes of the rear bank connecting the mud drum and rear upper drum, steam circulators connecting the front and rear upper drums, and steam circulators connecting the middle and rear upper drums; a com- 50 bustion chamber associated with the boiler; boiler tubes defining combustion space of said combustion chamber; downcomer means from said boiler to said last mentioned boiler tubes; and upcomer means from said last mentioned boiler 55 tubes to said boiler.

10. A bent tube boiler having two main natural circulation systems, each of said circulation systems including a steam and water drum, a group of upcomer tubes, and a group of downcomer 60 tubes, and means providing first and second gas passes in said boiler, said upcomer tubes of said two systems being located in the first gas pass and said downcomer tubes of said two systems being located in the second gas pass. 65

WILLIAM L. DE BAUFRE.
